A novel design for a granule dispenser, as shown and described.

DESCRIPTION

FIG. 1 is a side view of the granule dispenser with the opposite side being a mirror image;

FIG. 2 is a front view of the granule dispenser;

FIG. 3 is a rear view of the granule dispenser; and,

FIG. 4 is a top view of the granule dispenser; a bottom of the granule dispenser being unadorned and forming no portion of the design.
